UNITED STATES PATENT OFFICE.

GEORGE NOAH SCHELL, OF CLEVELAND, OHIO.

DESIGN FOR A VEHICLE-TIRE.

55,332.

Specification for Design.

Patented May 25, 1920.

Application filed November 21, 1919. Serial No. 339,735. Term of patent 3½ years.

To all whom it may concern:

Be it known that I, GEORGE NOAH SCHELL, a citizen of the United States, residing at Cleveland, in the county of Cuyahoga and State of Ohio, have invented a new, original, and ornamental Design for Vehicle-Tires, of which the following is a specification, reference being had to the accompanying drawing, forming a part thereof.

Figure 1, is a top plan view of a vehicle tire, showing my new design. Fig. 2, a transverse sectional view of the same.

I claim:

The ornamental design for a vehicle tire, as shown.

GEORGE NOAH SCHELL.
